Rolford D. Miller, Chicago, Ill.

Application December 14, 1950, Serial No. 13,432

Term of patent 14 years

(Cl. D85—2)

To all whom it may concern:

Be it known that I, Rolford D. Miller, a citizen of the United States, residing at Chicago, county of Cook, and State of Illinois, have invented a new, original, and ornamental Design for Combined Ash Tray, Cigarette Holder and Extinguisher, of which the following is a specification, reference being had to the accompanying drawing, forming a part thereof.

Figure 1 is a top plan view of a combined ash tray, cigarette holder, and extinguisher, showing my new design, and

Figures 2 and 3 are respectively side and rear elevational views thereof.

The dominant features reside in the part shown in full lines.

I claim:

The ornamental design for a combined ash tray, cigarette holder, and extinguisher, as shown and described.

ROLFORD D. MILLER.
